CLAIM

The ornamental design for a pad foot for a roller, substantially as shown and described.

DESCRIPTION

FIG. 1 is a front elevational view of a pad foot for a roller, showing my new design, the rear elevational view being a mirror image thereof;

FIG. 2 is a side elevational view thereof, the opposite side elevational view being a mirror image thereof;

FIG. 3 is a top plan view thereof;

FIG. 4 is a bottom plan view thereof;

FIG. 5 is a perspective view thereof; and,

FIG. 6 is a reduced perspective view.

The broken line showing in FIG. 4 and of the roller in FIG. 6 is for illustrative, environmental purposes only and forms no part of the claimed design.
